The ornamental design for a portable data transceiver, as shown and described.

DESCRIPTION

FIG. 1 is a perspective view of a portable data transceiver;

FIG. 2 is a front view thereof;

FIG. 3 is a top view thereof;

FIG. 4 is a right-side view thereof;

FIG. 5 is a left-side view thereof;

FIG. 6 is a rear view thereof;

FIG. 7 is a bottom view thereof; and,

FIG. 8 is another perspective view thereof.

The broken lines depict environmental subject matter only and form no part of the claimed design.
